STAND FOR DRIFT PUNCHES AND SET SCREW
WRENCHES

Isidore Polan, Brooklyn, N. Y.

Application November 10, 1955, Serial No. 38,854

Term of patent 14 years

(Cl. D80—9)

Fig. 2.

Fig. 1.

Fig. 3.

Fig. 4.

Fig. 5.

Fig. 1 is a front elevational view of a stand for drift punches and set screw wrenches, showing my new design.

Fig. 2 is a top plan view thereof.

Fig. 3 is a side view thereof, as seen from the right of Fig. 1.

Fig. 4 is a rear elevational view thereof.

Fig. 5 is a perspective view of said stand with drift punches and set screw wrenches shown in broken lines for purposes of illustration.

I claim:

The ornamental design for a stand for drift punches and set screw wrenches, substantially as shown and described.
